UNITED STATES PATENT OFFICE.

VINCEN P. McVOY, OF MOBILE, ALABAMA.

LUBRICATOR.

1,315,141.

Specification of Letters Patent. Patented Sept. 2, 1919.

Application filed February 9, 1918. Serial No. 216,208.

To all whom it may concern:

Be it known that I, VINCEN P. McVOY, a citizen of the United States, residing at Mobile, in the county of Mobile and State 5 of Alabama, have invented certain new and useful Improvement in Lubricators, of which the following is a specification.

This invention relates to lubricators and it has for its objects among others to provide an improved construction of lubricator which, while adapted for gravity feed in the usual manner under certain conditions, is designed primarily to be automatic, that is capable of being so set that the feed 15 shall be uniform and at a predetermined rate of speed and quantity, normally beyond the control of the engineer, and in no wise affected by variation of pressure in the steam pipe, that is, with the automatic 20 attachment the feed will be the same under heavy throttle pressure as under no pressure, hence, the feed will be the same whether the engine be drifting or running under steam pressure.

25 The present invention has for a further object to provide means which shall insure against hand manipulation of the valves by the engineer or other person to increase the feed, without detection. The construction, 30 however, is such that should from any cause the automatic feature become inoperative, the operator may break a seal and thus give him control of the feed until the automatic attachment is again put in order, when the 35 same is sealed against manipulation of parts to increase the feed beyond a predetermined quantity.

40 I employ a turbine operated by steam from the boiler through the lubricator, which turbine, in turn, operates a pump for delivering the oil to the different feeds and from thence into the cylinders by way of usual connections. The flow of oil through the different feeds is governed by the pump 45 and the latter is governed by the speed of the turbine. For this purpose, I employ a governor which can be set for various speeds, as may be required, to deliver any desired number of drops to the different 50 feeds, and the flow of steam to this turbine is controlled by a valve and when the latter is closed the device may be caused to feed by gravity by means of by-pass valves in the pump. The arrangement is such, 55 however, that should occasion require the

flow of oil in one or more feeds may be by gravity, even while the pump is running. This latter, of course, necessitates the breaking of the seal hereinbefore referred to. The by-pass valve for the air pump feed is at all 60 times accessible to the operator, whether the device be running under automatic or gravity feed, not being under the seal.

The present invention has for a further object to provide means for automatically 65 insuring proper distribution of the oil to the valves, as well as to the cylinders. As is well known, under ordinary conditions the oil intended for both the valves and the cylinders fed into the same from the lubricator is not equally distributed, that is, a portion 70 of the oil intended for the valves passes to the cylinders by reason of unequal pressure, the connections to the cylinders being open to the atmosphere one-half the time, 75 while those to the valves are not. Naturally, the oil takes the easier course, that is, to the cylinders. By the employment of check valves, I overcome this objection and insure the proper amount of oil going to 80 the valves instead of a portion thereof to the cylinders. The before-mentioned check valves prevent the back flow of the oil to the boiler through the steam pipe of the lubricator, and under excessive pressure the 85 check valve is seated so as to guard against this back flow of oil.

I may, sometimes, employ in connection with my present improvement means for facilitating or "boosting" the flow by 90 commingling a supplemental flow of steam with the oil, such as shown in a prior patent issued to me, but this is not absolutely essential 95 in connection with the novel features above outlined.

The pump employed is of novel construction, being valveless except for by-passes which may or may not be employed. The pump is geared to the turbine shaft and the parts so timed as to perform their functions 100 positively and reliably, whether the device be working under boiler pressure or void of pressure.

By my present improvement, instead of the operator being obliged to shut off each 105 and every feed manually and separately, as is common, I provide means whereby all feeds are simultaneously shut off by manipulation of a single valve, which latter controls the flow of steam to the turbine. The open- 110

ing of this valve to its fullest extent, however, will not allow delivery of a greater quantity of oil than that for which the governor of the turbine is set.

5 Other objects and advantages of the invention will hereinafter appear and the novel features thereof will be particularly pointed out in the appended claims.

In the present instance, I have shown 10 what, at the present time, I consider the preferable embodiment of my invention, but it is evident that the same is subject to changes, variations and modifications in 15 form, details of construction, proportions of parts, etc., without departing from the spirit of the invention or sacrificing any of its advantages. I, therefore, do not intend to restrict myself to the precise construction, proportion of parts, etc., herein disclosed, but 20 reserve the right to make such changes, variations and modifications as come properly within the scope of the appended claims.

The preferred form of embodiment of my invention is clearly illustrated in the accompanying drawings, which, with the numerals of reference marked thereon, form a part 25 of this specification, and in which—

Figure 1 is a front elevation of a lubricator constructed in accordance with my invention.

30 Fig. 2 is a rear elevation of the same.

Fig. 3 is a vertical section on the line 3—3 of Fig. 1, looking in the direction of the arrows.

35 Fig. 4 is a vertical section on the line 4—4 of Fig. 1, looking in the direction of the arrows.

Fig. 5 is a vertical section on the line 5—5 of Fig. 1, looking in the direction of the 40 arrows.

Fig. 6 is a substantially central longitudinal section through the pump.

Fig. 7 is an enlarged perspective view of 45 one of the plungers of the pump seen in Fig. 6.

Fig. 8 is a perspective detail with portions broken away, showing a portion of the crank shaft of the pump.

Fig. 9 is a sectional detail showing the 50 connection of a pipe leading from the pump to one of the sight feeds of the lubricator.

Fig. 10 is a detail of the governor for the turbine.

Like numerals of reference indicate like 55 parts throughout the several views.

My improved lubricator as herein illustrated and now to be described is designed to be attached in any suitable way to the boiler or other fixed portion of the lubrica-

60 tor or other engine. One convenient form of means of attaching or supporting the lubricator is seen in Figs. 2 and 3 in the form of lugs or the like 1. It is evident, however, that the lubricator may be attached in any other well known way.

2 is the reservoir or body portion of the lubricator provided with the usual peep sight 3 for a well known purpose, 4 being the filling plug, also of known construction.

5 is the drain valve for draining the water 70 from the reservoir 2, as is usual in this class of devices.

6 are the sight feeds or peep glasses, of 75 which there may be any desired number according to conditions under which the lubricator is to be used, in the present instance shown as five in number merely for the purpose of illustration. 7 are regulating valves for the sight feeds, operable by hand singly 80 in the usual way, but when my automatic mechanism now to be described is in operation these valves are capable of being turned to diminish the flow of oil, but cannot be turned to increase the flow of oil beyond an amount predetermined by the adjustment of 85 the governor in the turbine, as will soon be made clear.

8 are pipes extending one from each valve 90 chamber 9 of the sight feeds 6 to a pump, soon to be described, and through which the oil is pumped by said pump into the sight feeds 6. 10 is the feed or intake pipe for oil from the reservoir to the pump.

11 is a condenser provided with a coupling 95 12 or any suitable means for containing a strainer and one member, as 13, designed for connection with a source of steam supply, as with the steam space of the boiler, the other end being closed by a plug, as shown at 12' in Figs. 1 and 2. 14 is a pipe 100 connecting this condenser with the lower portion of the reservoir 2, as seen best in Fig. 3, so as to convey the water of condensation to the lower portion of the reservoir beneath the oil therein. 15 is a hand-operated valve by which the flow of steam through the condenser is permitted, or shut off for the purpose of refilling the lubricator.

16 is a hand-operated valve for controlling the flow of steam from the boiler through 110 the condenser 11 into the passage 17 in the upper portion of the reservoir 2, as seen in Fig. 3. From this passage or chamber 17, there extends a passage 18, as seen best in Fig. 3, beneath a check valve 19 which controls a passage 20 down one side of the body portion of reservoir 2, as seen in Fig. 3, this passage communicating with a chamber 21, as clearly seen in Fig. 3. Leading from this chamber 21 is a passage 22 through a 115 nipple or the like 23 designed for connection in the usual way with the part to be lubricated.

24 is a steam pipe provided with a valve 120 25 and this pipe is connected with the steam space of the boiler or other suitable source of steam supply and with the manifold 26, as seen clearly in Figs. 2 and 3. From this manifold there extend, in the present instance, four connections 27, as seen in Figs. 125 130

2 and 3. In each of these connections 27 is a check valve 28, as seen clearly in Fig. 3, which controls a passage 29 from the chamber 30 to the passage 22.

5 From the chamber 21 extends a passage 31 through a partition 32 in the body portion 2 of the reservoir and this passage 31 communicates by the vertical passage 33 with the corresponding peep glass 6, as seen clearly in Fig. 3.

10 At one end of the reservoir or body portion 2 of the lubricator, I support in any suitable manner a casing or chamber 34 within which is a turbine 35 carried by a 15 shaft 36 mounted in suitable bearings for free movement, carrying at one end a worm 37, as seen in Fig. 3, which meshes with a worm gear 38 on a shaft 39 mounted in a suitable bearing or casing 40, as seen best 20 in Fig. 1, which shaft 39 carries at its upper end a worm 41 meshing with a worm gear 42 on the pump shaft 43, as will be clearly understood upon reference to Fig. 3. 44 is the end bearing for the shaft 39, the same 25 being removable and adjustable and designed to carry the end thrust, as will be readily understood.

30 45 is the pump cylinder secured in any suitable manner to the body 2 of the lubricator. In the present instance, I have chosen to show the pump cylinder as provided with lugs or the like 46, as seen in Fig. 1, to receive the screws or the like 47 for this purpose.

35 48 is a packing gland about the shaft 43 within a casing or chamber 49, as seen best in Fig. 6.

40 50 is the end member of the stuffing box or gland and this further constitutes the end of the pump cylinder, the other end 51, as seen in Fig. 6, being removable and adapted to form a support for the adjacent end of the crank shaft 52 of the pump. The 45 opposite end member 50 is also removable and between the same and the collar 53, rigid with the shaft 43, is an end thrust roller or ball bearing 54, as seen clearly in Fig. 6. The shaft 43 revolves, but the shaft 52 is fixed or relatively stationary, but with 50 the shaft 43 there revolves the pump body or plunger 55 which is interlocked at its end with the adjacent end of the shaft 43 in any suitable or convenient manner.

55 The crank shaft 52 fits the bore of the cylinder or casing 45 except at predetermined points throughout its length where the diameter of the said shaft 52 is reduced, as seen at 56, see Fig. 8. These reduced portions 56 constitute cranks and there are 60 as many of these cranks in the shaft 52 as there are feeds to the lubricator. Corresponding in position with each of these cranks the pump casing 45 is provided with nipples or the like 57, screw-threaded, as at 65 58, for the attachment of the pipes 8. At

points diametrically opposite the bores or passages of the nipples or the like 57, the wall of the casing 45 is provided with passages or the like 59, as seen in Fig. 6, which communicate with a chamber 60 extending 70 substantially the full length of the pump and the outer wall of this chamber is provided with suitable means, as 61, for connection of the intake pipe 10 which connects, as at 62, see Fig. 1, with the reservoir 2 of 75 the lubricator.

The rotating member 55 of the pump is provided with the peripheral substantially semi-circular grooves or passages 63 and 64, the grooves or passages 63 communicating 80 at the top with the passages 59 hereinbefore referred to, and the passages 64 communicating at the bottom with the downwardly extended passages 65 which communicate, by means of the passages 66 in the couplings 67, 85 with the pipes 8, as will be readily understood upon reference to Figs. 4 and 1.

The pump casing 45 is provided at the rear with extensions 68, as seen clearly in Figs. 4 and 5, and in each of these extensions 90 is the upper substantially horizontal passage 69 communicating with the chamber 60 and this passage 69, in turn, communicates with the vertical passage 70, the lower end of which communicates, by means of the 95 substantially horizontal passage 71, with the passage 65 just described, all as clearly illustrated in Fig. 4.

Within each extension 68, at the junction of the passages 69 and 70, is a seat for a 100 check valve 72, see Fig. 4, 73 being a spring acting to normally seat the valve, and the extension or stem 74 of this check, when the check is seated, terminates slightly above the end portion 75 of a stem 76, which end portion traverses the passage 70 and is provided with a cam portion 77, as seen clearly in Fig. 4. When this stem 76 is turned by means of its thumb nut or the like 78, the cam portion 77 lifts the check 72 from its 105 seat. When the stem is turned back to its normal position, the spring 73 seats the valve, the cam portion 77 being moved away from the adjacent end of the stem, all of which will be clearly understood upon reference to Fig. 4. The stem 76 passes through a stuffing-box 79 on the extension 68, for an 110 obvious purpose.

115 These details, however, as well as many others, pertaining to the construction, may be varied as occasion may require, so long as the same function and result are attained. The particular construction of turbine employed is not essential and the present invention is not restricted in this respect, either 120 in the particular form of turbine or the particular construction of the governor soon to be described.

125 The member 45, through which the shaft 52 passes, is provided with alternate parti-

tions and chambers and between each two partitions works one of the reciprocatory plungers of the pump. In the drawings, these partitions are indicated by the reference numeral 80 and are seen best in Fig. 6. The chambers between these partitions are indicated by the numeral 81. In each of these chambers works one of the plungers. As these plungers are all alike, a detailed description of one will suffice for all. In Fig. 7 there is shown an enlarged detail view of one of such plungers 82 which is in the form of a cylinder hollow for a portion of its length, the lower end being closed, as shown at 83 in Figs. 4 and 7, and the upper end internally threaded, as at 84, for the reception of a screw-threaded plug 85, see Fig. 4, projecting from the lower end of which is a portion 86 extended beyond the threads, as seen in Fig. 4, and designed for contact by a cam 56 of the cam shaft 52, whereby the plunger is reciprocated back and forth by the action of the cam 56, as the member 55 revolves, carrying the plungers therewith, the result being substantially the same as if the cam shaft revolved and the member 55 remained stationary, but by the construction shown the member 55 constitutes valves, both intake and discharge, and the employment of extraneous valves is obviated, together with the inherent disadvantages of separate valves.

The member 55 has at diametrically opposite sides the clearance spaces 87 and 88, with the former of which the groove or passage 63 communicates at one end, while the passage 64 communicates with the other clearance space at the diametrically opposite end or point, as seen clearly in Fig. 4. 89 is a pipe leading from the steam portion of the reservoir 2 and connected at 90 to the governor valve which is located within the chamber 91 at the end of the turbine casing 34. This governor may be of any well-known type adapted to the purpose. In the present instance, I have chosen to show a form of governor which I have found efficient and which serves its purpose most satisfactorily. This governor in detail is illustrated in Fig. 10, to which attention is now directed. This governor valves comprises a valve member 92 reciprocating within the casing 93 and, in alignment therewith, is a pin 94 for loose reciprocation in the upper end of the casing 91 with its lower end resting upon a flat surface 95 on the curved lever 96 pivotally mounted, as at 97, within the casing 91 and its free end bearing against a pin 98 mounted to reciprocate loose within the member 99 and at all times under the control of the governor balls or weights 100 pivotally mounted, as at 101, upon some part fixed to and movable with the turbine wheel 35, as shown in said Fig. 10. 102 is a spring acting in opposition to the

governor weights, the construction being such that as the speed of the turbine increases, centrifugal force throws the weights out, moving the pin 98 in the direction of the arrow in Fig. 10, moving the lever 96 in the direction of the arrow connected therewith and forcing the governor valve 92 in the direction of the arrow thereon in said Fig. 10, shutting off the steam proportionately.

In order that the device may be so set that manipulation of the valves 7 by the engineer or operator cannot, by any possibility, increase the amount of oil to be fed to the engine, I provide a seal or lock for the wheels 78 which control the check valves 72. 80 This seal or lock may be of any desired character. In the present instance, I have chosen to show the wheels 78 as provided with openings 103, through which may be passed a wire or the like 104 which may be sealed by any well-known form of seal, as at 105. The central valve, however, is not included in the seal. The two valve wheels at the right are thus connected and sealed and the two on the left are likewise sealed. The middle one, however, is left unsealed in order that this, which is the air pump feed, may have the same pressure in its steam at all times as the same is not controlled by hand throttle. Under ordinary conditions, 90 these valves are locked and sealed, so that they cannot be manipulated by the engineer or operator; but, should, perchance, anything go wrong with the automatic mechanism hereinbefore described, the engineer or 100 operator, by breaking the seal, can convert the lubricator into the ordinary gravity feed until the necessary repairs are made.

Also, in order to guard against removal of the plugs 106, which permit access to the 105 check valves 72, from being removed to remove the valves 72 and overcome the necessity of breaking the seals, I lock all of these plugs by means of a wire seal 107, as seen clearly in Fig. 1, which wire is passed 110 through openings 108 in all of the said plugs, including the middle one, and then sealed in any well-known or desired way.

With the parts constructed and arranged substantially as hereinbefore described, the 115 operation, briefly stated, is substantially as follows:

The parts being operatively connected with the steam space of the boiler and the various connections being made as hereinbefore described and as illustrated, and steam being admitted from the boiler or other suitable source of steam supply, through the strainer at 12 and into the condenser 11, and the valve 15 being open, 120 steam or the water of condensation is admitted through the pipe 14 into the bottom part of the reservoir 2 beneath the oil therein, as will be readily understood upon reference to Fig. 3. The valve 16 also must be 125

opened. Steam is then admitted to the turbine through the pipe 89 by turning the valve handle 89^a seen in Fig. 1. This imparts motion to the turbine 35 and through the medium of the turbine shaft 36, the worm 37, the worm gear 38, the shaft 39, the worm 41 and the worm gear 42, rotary motion is imparted to the shaft 43. The shaft 43 being coupled up with the rotary pump member 55, the latter is rotated with the shaft 43, the shaft 52 with its cams 56 remaining stationary as hereinbefore described, and not revolving, the plungers 82 are reciprocated back and forth, it being understood that the plungers are arranged not all in parallel alinement with but disposed about the member 55 so as to extend at different angles for operation to supply oil at different times to the various feeds. Furthermore, this arrangement relieves the turbine of its load, as all of the plungers are not discharging against pressure at the same time, some intaking and others discharging, as will be readily understood. So long as these conditions exist, the oil is automatically fed to the feeds 6 through the pipes 8 and from thence through the passages 33 and 31, the chamber 21 and passage 22 to the part to be lubricated. The flow of oil through each feed takes place in the same way. The valve 16 being open, steam passing down through the condenser enters the passage 17 which is common to all of the feeds and, passing through the passage 18, under the check 19, and opening the same, flows downward through the passage 20 into the chamber 21 in greater quantities than can escape through the choke bore in the inner end of the coupling 23, thus creating pressure on both sides of the oil, these pressures being practically balanced, or, possibly, slightly in favor of the gravity feed, thus insuring practically uniform feed.

In order to "boost" or facilitate or rush the flow of oil after it enters the passage 22 in the coupling 23 on its way to the part to be lubricated, steam is admitted to the pipes 24 by opening the valves 25 and this steam then passes into the manifold 26, lifting the check valves 28 from their seats, and then the steam flows through the passage 29 and through the openings in the coupling 23 into the passage 22 and, commingling with the oil, hastens the flow thereof. It will be understood, of course, that the pipe leading from the coupling 23 to the engine or the parts to be lubricated is of considerable length, generally from twenty to twenty-five feet, and this "boosting" of the oil is of material advantage. These check valves 28 serve to prevent back flow of the steam from one feed to another through the passage 29.

As constructed, with the valve handles 78 locked and sealed and the plugs 106 also being secured and sealed, there is no way for

the engineer or operator to manipulate any of the parts to increase the feed. The valves 7 may be manipulated to decrease the flow of oil through any one or more of the feeds, but not to increase it. Should, however, from any cause, the lubricator fail to work in the manner just described, the engineer or operator is authorized to break the seals 105, when the hand wheels 78 may be turned so as to reverse their positions and allow the lubricator to work as a gravity feed lubricator until the necessary repairs are made. For convenience, the hand wheels 78 are provided with some suitable indicia, such, for instance, as "P",—indicating "pump",—and "G",—indicating "gravity",—so that the operator can tell at a glance whether these valves are set for the gravity or automatic or pump feed. When the valve stems 78 are turned from their automatic or pumping position to that for gravity feed, the valves 72 which, under automatic feed are seated, are lifted from their seats by the cams 75, as will be readily understood upon reference to Fig. 4.

The seal 107 is supposed never to be broken unless it becomes necessary to remove the plugs 106 for repairs or some other purpose. If this seal is broken, the valves 72 might be tampered with and this it is essential to guard against.

The speed of the turbine and the consequent speed of the pump and feed of the oil is controlled by the governor mechanism shown in Fig. 10, a heavier spring 102 being employed for greater speed and a lighter spring for less speed.

It will be apparent that each plunger 82 of the pump is provided with an opening 82^a, as seen clearly in Fig. 7, through which the openings on the crank shaft 52 pass. See also Fig. 6 in which all of the plungers are shown.

What is claimed as new is:—

1. In a lubricator, a positively driven automatic feed device convertible into a gravity feed, a delivery pipe common to both of said feeds, and mechanism insuring that there shall be no gravity feed when the automatic feed is in action.

2. In a lubricator, a positively-driven automatic feed device, convertible into a gravity feed, a delivery pipe common to both of said feeds, means for locking the gravity feed out of action while the automatic feed is in action, and means for bypassing the oil for gravity feed.

3. In a lubricator, a pump operatively connected, a pressure feed, a gravity feed, a by-pass for the oil under gravity feed, and means for locking the gravity feed out of action while the pressure feed is acting.

4. In a lubricator, an oil pump, operative means connected therewith, feed devices operable with or without the pump, a by-

pass for the oil under gravity feed, and means to lock the one feed out of action while the other feed is acting.

5. In a lubricator, an oil pump, operative means connected therewith, feed devices operable with or without the pump, a bypass for the oil under gravity feed, means to lock the one feed out of action while the other feed is acting, and means for controlling the said first-named means.

6. In a lubricator, an oil pump, operative means connected therewith, feed devices operable with or without the pump, a bypass for the oil under gravity feed, means to lock the one feed out of action while the other feed is acting, and means for accelerating the flow of the lubricant in its passage from the lubricator.

7. In a lubricator, an oil pump, operative means connected therewith, feed devices operable with or without the pump, a bypass for the oil under gravity feed, means to lock the one feed out of action while the other feed is acting, and means whereby a predetermined flow of the lubricant cannot be exceeded.

8. In a lubricator, an oil pump, operative means connected therewith, feed devices operable with or without the pump, a bypass for the oil under gravity feed, means to lock the one feed out of action while the other feed is acting, means for controlling the first-named means, and means whereby a predetermined flow of the lubricant cannot be exceeded.

9. In a lubricator, a pump operatively connected, a pressure feed, a gravity feed, a bypass for the oil under gravity feed, means to lock the gravity feed out of action while the pressure feed is acting, and a lubricant-flow-accelerating device.

10. In a lubricator, a pump operatively connected, a pressure feed, a gravity feed, a bypass for the oil under gravity feed, means to lock the gravity feed out of action while the pressure feed is acting, a lubricant-flow-accelerating device, and means for preventing an excess flow of the lubricant.

11. In a lubricator, a non-rotatable crank shaft, a member rotatable about the same, means for rotating said member and reciprocatory plungers coöperating with the cranks of the crank shaft and movable in said member and disposed at relatively different angles with relation to the axis of the said member.

12. In a lubricator, a non-rotatable cam shaft, a member rotatable thereon, and having peripheral passages and plungers mounted for reciprocation in said member, said member having means constituting valves and governing the intake and discharge of the oil.

13. In a lubricator, a non-rotatable cam

65 shaft, a member rotatable thereon, plungers

mounted for reciprocation in said member, said member having means constituting valves and governing the intake and discharge of the oil, and a by-pass embodying a check valve.

14. In a lubricator, a non-rotatable cam shaft, a member rotatable thereon, plungers mounted for reciprocation in said member, said member having means constituting valves and governing the intake and discharge of the oil, a by-pass embodying a check valve, and cam means for unseating said valve.

15. In a lubricator, positively-driven automatic oil feeding means, sight feeds, a by-pass for the oil under sight feed, valves controlling the same, a gravity feed, means to lock the gravity feed out of action while the automatic feed is acting and means whereby flow of oil beyond a predetermined amount is prevented.

16. In a lubricator, positively-driven means for automatic or gravity feed, a by-pass for the oil under gravity feed, and means for locking the parts against change from automatic to gravity feed.

17. In a lubricator, a pump, means for actuating the same, a sight feed, a by-pass for the oil under sight feed, and a valve operable for use of the device as either automatic or gravity feed and means to lock the gravity feed out of action while the automatic feed is acting.

18. In a lubricator, a pump, means for actuating the same, a sight feed, a by-pass for the oil under sight feed, a valve operable for use of the device as either automatic or gravity feed, and locking means to prevent manipulation of said valve while the automatic feed is acting.

19. In a lubricator, a non-rotatable cam shaft, an annular member rotatable thereon, and having peripheral passages and a reciprocable plunger in said member coöperating with the cams of said cam shaft, and means for revolving said member.

20. In a lubricator, a non-rotatable cam shaft, an annular member rotatable thereon, and a reciprocable plunger in said member coöperating with the cams of said cam shaft, and means for revolving said member, said member having diametrically opposite grooves upon its periphery.

21. In a lubricator, a non-rotatable cam shaft, an annular member rotatable thereon, and a reciprocable plunger in said member coöperating with the cams of said cam shaft, means for revolving said member, said member having diametrically opposite grooves upon its periphery, and a by-pass adapted to be alternately put in communication with said grooves.

22. In a lubricator, a non-rotatable cam shaft, an annular member rotatable thereon, and a reciprocable plunger in said member

coöperating with the cams of said cam shaft, means for revolving said member, said member having diametrically opposite grooves upon its periphery, a by-pass adapted to be 5 alternately put into communication with said grooves, and a check valve in said by-pass.

23. In a lubricator, a non-rotatable cam shaft, an annular member rotatable thereon, 10 and a reciprocable plunger in said member coöperating with the cams of said cam shaft, means for revolving said member, said member having diametrically opposite grooves upon its periphery, a by-pass adapted to be 15 alternately put in communication with said grooves, a check valve in said by-pass, and

a cam member for unseating said check valve.

24. In a lubricator, a rotary pump, a turbine for actuating the same, means for introducing steam into the lubricant after it leaves the lubricator for hastening its flow to the parts to be lubricated, and means whereby a predetermined flow of the lubricant cannot be exceeded. 20

25. In testimony whereof I affix my signature in the presence of two witnesses.

VINCEN P. McVOY.
